FLEXIBLE MOUNTING CYLINDER WASHER
AND EXTRACTOR MECHANISM

Leslie E. Soderquist, Akron, Ohio, assignor to National Rubber Machinery Company, Akron, Ohio, a corporation of Ohio

Application October 4, 1937, Serial No. 167,137

8 Claims. (Cl. 210—71)

This invention pertains to a mounting arrangement for high speed centrifugal extractors and the like and, more particularly, to a mounting arrangement for a washing or cleaning machine drum or cylinder extractor and its drive mechanism. The invention will be disclosed herein in an application to a cleaning machine extractor drum disposed for rotation on a horizontal axis.

One of the primary objects of the invention is to provide a mounting which will support the cylinder or drum in such manner that the cylinder may be rotated at a relatively high speed for the extraction of water, solvent, or other cleaning fluid without excessive vibration should there be an unbalanced condition due to uneven or unequal loading in the cylinder or drum or to other causes.

Another object is to provide a mounting of the character described wherein the cylinder or drum and its drive mechanism will be thoroughly, and substantially completely, insulated electrically and mechanically from any other mechanism with which the same may be associated.

A further object is to provide a structure of the character mentioned which is simple, compact and efficient and which is capable of long life under sustained high speeds and heavy loads.

A still further object is to provide a structure of the character described in which the cylinder and its drive mechanism are so mounted and insulated as to provide for quiet operation.

Many other objects as well as the advantages, uses and adaptations of the invention will be or should become apparent and well understood after reading the following description and claims and after viewing the drawings, in which:

Fig. 1 is a rear elevation view of a cleaning machine in which the invention may be embodied, a portion being broken away to disclose the location of the centrifuge or drum and its drive mechanism with relation to the machine as a whole;

Fig. 2 is a large scale view in side elevation and partly in section showing a preferred mounting arrangement and construction for the cylinder or drum and its driving mechanism; and

Fig. 3 is a large scale view in rear elevation with parts broken away, the view being taken substantially from the line III—III of Fig. 2 and looking in the direction of the arrows.

The rear frame of the washing or cleaning machine is designated 10. Within this frame is a tub, the outline of which is shown in dotted lines and designated 11. The extractor cylinder

is indicated by the dotted line 12 while 13 indicates the drive pulley on the driving mechanism and 14 a belt running over the pulley to drive the same from any convenient source of power. Certain braces for supporting the extractor and its driving mechanism are shown in dotted outline in Fig. 1 and are designated 15, 16, 17 and 18. These braces extend from the several corners of the machine cabinet or frame to the extractor as will be more clearly apparent as the description proceeds.

In Figs. 2 and 3 braces 17 and 18 are illustrated at those places where they are joined to certain structural mechanism to be described. The channel member 19 extends transversely between the braces 15 and 18 and is secured thereto, while a ring member 20 is secured to and supported by the braces 15, 16, 17 and 18. The ring member 20 carries a ring member 21, the central section of which is composed of rubber, the outside members being of steel which may be vulcanized or otherwise secured to the rubber section.

A gear case 22, having an end portion 22', contains the transmission gearing including 25 change speed gearing for driving the cylinder or drum 12. A ring bracket member 23 is carried by a ring support 24, which in turn is carried and supported by a bracket 25 attached to the brace 19. The ring bracket 23 carries a 30 steel band or the like 31 within which and between which and a steel band 32 carried by the end portion 22' of the gear case, is a rubber band or ring 26. The ring member 26 is similar to the ring 21 in construction in that it may be 35 vulcanized to the steel rings 31 and 32. A drive shaft 33 projects from the casing 22' and supports the pulley 13 which is secured thereto in any suitable manner.

The drum or cylinder 12 is supported upon a 40 driving shaft 29 which extends out of the gear casing 22 and which may be secured to the cylinder or drum in any suitable manner. Mounted on the wall of the cylinder about the shaft 29 is a spinner designed to prevent dirt or liquids from entering the gear case. Inasmuch as the torque of rotation of the cylinder or drum might tend to rotate the gear case and its associated mechanism, and inasmuch as the cylinder or drum may be rotated in either of opposite directions, lugs 28 may be formed on opposite sides of the gear case to provide abutments for springs 27 which at their lower ends rest in recesses in the bracket 25. The springs are adapted to yield to a slight extent under certain torque and load 55

conditions and of themselves will tend to absorb considerable vibration. These springs 27, however, are mounted as closely as possible to the center of mass of the entire cylinder and the 5 gear case mechanism when the cylinder is in loaded condition.

The operation of the device may be described as follows: The pulley 13 is driven by the belt 14 from any suitable source of power such as an 10 electric motor (not shown) and in turn drives the cylinder or drum 12 through the transmission mechanism or gearing contained within the gear case. The arrangement is such that the cylinder is driven at a slow speed for the washing operation and ordinarily will be rotated in one direction for one or more revolutions and then in the opposite direction for one or more revolutions, the alternation continuing over such time as may be deemed necessary to wash the clothes or other 20 items within the cylinder 12. When the washing has been completed the speed of the cylinder is increased through the gear mechanism within the gear case, the speed being increased gradually to deposit the clothes or load within the cylinder as 25 uniformly as possible around the periphery of the cylinder. This gradual increase of speed has been found to result in a fairly uniform loading of the clothes within the cylinder.

Since it is practically impossible to secure absolutely uniform loading about the periphery of the cylinder, the dynamic balance thereof is bound to be disturbed and this out of balance condition would result in excessive vibration at high speed even to the point of tearing the machine to pieces. However, with the construction described the cylinder and transmission tend to swing about the axis 34', the resulting gyration describing a cone, the apex of which is at the point 34 on the normal axis. In other words the 40 resultants of any unbalanced forces will be resolved or will tend to resolve themselves into gyroscopic forces so swinging the drum or cylinder, the transmission and parts immediately carried by them, that points thereon will move in circular paths about the normal axis 34-34' and which paths lie in a cone or cones the apex or apices of which lie at approximately the mean center of the resilient member 26 and on a projection of the normal axis of rotation of the 45 drum or, in other words, substantially at the point 34, while the base of the cone may lie between the lines 35-35'. However, while the torque effect on the transmission, the transmission casing and associated parts tends to rotate 50 them with the drum, such tendency is resisted by the springs 27 which still permit points on the casing and on the transmission to describe relatively circular paths as mentioned.

The ring 26 extends axially of the drum shaft 60 and forms a radial connection between radially spaced elements 22 and 23. The ring 21 extends axially of the drum shaft and forms an axial connection between axially spaced elements 20 and 22. Ring 26 thus permits the slight movement of the driven end of the shaft about the point 34 while holding the pulley 13 or other driven element in proper line with the motor or other source of power not shown. Ring 21, however, permits greater freedom of movement of the drum shaft radially under an unbalanced load and absorbs the vibrations thereof which are not transmitted to the frame of the machine. These two mountings permit the shaft of the 75 drum to find the axis of rotation under an un-

balanced load about which the load tends to become balanced.

While I have illustrated and described a preferred embodiment of the invention and one use to which the invention may be put, it is susceptible of various modifications and of other uses without departing from the spirit of the invention and the scope of the appended claims.

I claim:

1. A centrifuge drier comprising a cage rotatable about a horizontal axis, a drive shaft connecting said cage and concentric therewith, means for rotating said shaft, and spaced members for supporting said shaft, one of said members adjacent said cage including a fixed element, 15 an element in axially spaced relation to the fixed element for rotatably supporting said shaft and a ring of elastic or resilient material forming an axial connection between said axially spaced elements, the other of said members more remote 20 from said cage including a fixed element on said frame, an element in radially spaced relation to the fixed element for rotatably supporting said shaft and a ring of elastic or resilient material forming a radial connection between said radially 25 spaced elements.

2. A centrifuge drier comprising a cage rotatable about a horizontal axis, a drive shaft connecting said cage and concentric therewith, 30 means for rotating said shaft, and spaced members for supporting said shaft, one of said members adjacent said cage including a fixed annular element, an annular element in axially spaced relation to the fixed element for rotatably supporting said shaft and a ring of elastic or resilient material 35 forming an axial connection between said axially spaced elements, the other of said members more remote from said cage including a fixed annular element on said frame, an annular element in radially spaced relation to the fixed 40 element for rotatably supporting said shaft and a ring of elastic or resilient material forming a radial connection between said radially spaced elements.

3. A centrifuge drier comprising a cage rotatable about a horizontal axis, a drive shaft connecting said cage and concentric therewith, means for rotating said shaft, spaced members for supporting said shaft, one of said members adjacent said cage including a fixed element, 50 an element in axially spaced relation to the fixed element for rotatably supporting said shaft and a ring of elastic or resilient material forming an axial connection between said axially spaced elements, the other of said members more remote 55 from said cage including a fixed element, an element on said frame in radially spaced relation to the fixed element for rotatably supporting said shaft and a ring of elastic or resilient material forming a radial connection between said radially 60 spaced elements, and yieldable means independent of both of said supporting members for yieldingly resisting the torque of rotation of said cage.

4. A centrifuge drier comprising a cage rotatable about a horizontal axis, a drive shaft connecting said cage and concentric therewith, means for rotating said shaft, and spaced members for supporting said shaft, one of said members adjacent said cage including a fixed annular element, 65 an annular element in axially spaced relation to the fixed element for rotatably supporting said shaft and elastic or resilient means forming an axial connection between said axially spaced elements, the other of said members more remote 70 from said cage including a fixed element, an element on said frame in radially spaced relation to the fixed element for rotatably supporting said shaft and elastic or resilient means forming a radial connection between said radially 75 spaced elements.

from said cage including a fixed annular element, an annular element in radially spaced relation to the fixed annular element for rotatably supporting said shaft and elastic or resilient means forming a radial connection between said radially spaced elements.

5. A centrifuge drier comprising a power mechanism including a relatively non-rotating casing, a driven shaft connected with said power mechanism, a cylindrical drum concentrically secured to the end of said shaft, and spaced members surrounding said mechanism for supporting said casing, one of said spaced members adjacent said drum including a fixed element, an element mounted on said casing in axially spaced relation to the fixed element and elastic or resilient means forming an axial connection between said axially spaced elements, the other of said members more remote from said drum including a fixed element, an element mounted on said casing in radially spaced relation to the fixed element and elastic or resilient means forming a radial connection between said radially spaced elements.

25. 6. A centrifuge drier comprising a power mechanism including a relatively non-rotating casing, a driven shaft connected with said power mechanism, a cylindrical drum concentrically secured to the end of said shaft, and spaced members surrounding said mechanism for supporting said casing, one of said spaced members adjacent said drum including a fixed annular element, an annular element mounted on said casing in axially spaced relation to the fixed element and a ring of elastic or resilient material forming an axial connection between said axially spaced elements, the other of said members more remote from said drum including a fixed annular element, an annular element mounted on said casing 40 in radially spaced relation to the fixed element

and a ring of elastic or resilient material forming a radial connection between said radially spaced elements.

7. A centrifuge drier comprising a power mechanism including a relatively non-rotating casing, a driven shaft connected with said power mechanism, a cylindrical drum concentrically secured to the end of said shaft, spaced members surrounding said mechanism for supporting said casing, one of said spaced members adjacent said drum including a fixed element, an element mounted on said casing in axially spaced relation to the fixed element and elastic or resilient means forming an axial connection between said axially 15 spaced elements, the other of said members more remote from said drum including a fixed element, an element mounted on said casing in radially spaced relation to the fixed element and elastic or resilient means forming a radial connection 20 between said radially spaced elements, and resilient means associated with said casing for resisting torque thereof.

8. A centrifuge drier comprising a cylindrical centrifugal drum, a drive shaft connecting said drum and concentric therewith, means for rotating said shaft, and axially spaced members for supporting said shaft, one of said members adjacent said drum including fixed means, means in axially spaced relation to the fixed means for rotatably supporting said shaft and elastic or resilient means forming axial supporting connection between said axially spaced means, the other of said members more remote from said drum having fixed means, means in radially spaced relation to the fixed means for rotatably supporting said shaft and elastic or resilient means forming radial supporting connection between said radially spaced means.
